UNITED STATES PATENT OFFICE.

WILLIAM L. MORRIS, OF CHICAGO, ILLINOIS.

HIGH-SPEED RECORDING-GAGE.

1,052,940.

Specification of Letters Patent. Patented Feb. 11, 1913.

Application filed January 25, 1904. Serial No. 190,544.

To all whom it may concern:

Be it known that I, WILLIAM L. MORRIS, a citizen of the United States, resident of Chicago, county of Cook, and State of Illinois, have invented a new and useful Improvement in High-Speed Recording-Gages, of which the following is a specification, the principle of the invention being herein explained and the best mode in which I have 10 contemplated applying that principle, so as to distinguish it from other inventions.

My invention relates to recording gages, and particularly to such gages as are designed to have a plurality of cycles or turns 15 whereby a high speed of revolution or reciprocation can be obtained, and, consequently, a very detailed record of the varying pressures that are measured.

Said invention consists of means herein- 20 after fully described and specifically set forth in the claims.

The annexed drawings and the following description set forth in detail certain mechanism embodying the invention, such dis- 25 closed means constituting, however, but one of the various mechanical forms in which the principle of my invention may be applied.

In said annexed drawings:—Figure 1 repre- 30 sents a vertical longitudinal section of a form of mechanism embodying my invention; Fig. 2 represents a horizontal section taken upon the plane represented by the line 2—2, Fig. 1; Fig. 3 represents a diagram of 35 a chart used with the mechanism illustrated in Figs. 1 and 2; Fig. 4 represents the chart as it would be when rolled into position and gummed upon the drum; Fig. 5 represents a side elevation of the rock-shaft that oper- 40 ates the marker; Fig. 6 represents the lower end of the drum-supporting screw and the stop-pin to prevent the drum from falling off; Fig. 7 represents a vertical section taken 45 upon the plane indicated by the line 7—7, Fig. 8, the parts being developed into a straight line to aid in showing the details; and Fig. 9 shows a plan of the clock mechanism used to operate the revolving cylinder.

The object of my invention is to design a 50 recording gage that can be operated at a greater speed than those which have been heretofore in use, and at the same time provide a chart upon which the pressures can be recorded and which are readily adapted 55 for filing away for reference.

In my invention I obviate the difficulties

heretofore connected with the use of chart supporting mechanisms of limited area by providing means whereby charts carried by said mechanisms are passed by the marking 60 instrument a plurality of times; also by providing means whereby the relative positions of said chart and said marking instrument are changed at each cycle so as to present a new portion of the chart to the marking 65 instrument each time. The mechanism adapted to meet these requirements is not material, and may assume a great number of forms comprising a cylindrical supporting member adapted to revolve and simultane- 70ously move axially, thereby bringing a new portion of the chart into the path of the marking instrument every revolution; thus the drawings presented herewith, to which reference has been made, and in which the 75 same reference letters refer to like parts, is shown my preferred form of apparatus for securing the plurality of cycles of movement of the supporting member for the recording chart, and the means for presenting different 80 portions of said chart to the marking instrument at each cycle.

The chart supporting member is a cylindrical drum A, Figs. 1 and 2. This drum is carried by a screw B, which is supported by 85 the cross-arm C and the posts C'. The latter are received in the base or body D by means of the tapped bosses D². Flanges D' are provided for the body D, whereby it may be attached to a wall by means of bolts in 90 the holes D². This body D is in the form of a box with the front end open and provided with a hinged door D³ with glass D⁴ in the same. The flanges D' are placed above and below the box at the back of the same, as indicated in dotted lines in Fig. 2. Two large circular openings are provided in the case through which the drum may pass, and rims D⁵ are stiffening edges for these openings. A Bourdon spring for giving movement to 100 the marker is shown at E with a nipple E' for pipe connection of the same with the pressure to be measured. Pivot screw E² connects the spring to the marker mechanism. The marker pen is shown at F with an arm F' to carry the same, the latter being connected to a bell-crank F² which is carried on a pivoted shaft F³. This latter shaft is supported on needle points in the supports F⁴ which screw into the body or 110 case D. The screw F⁵ is provided by means of which the marker may be withdrawn the

required distance from the chart. A second screw F^6 is provided for preventing the marker from bearing too heavily upon the chart. The latter thus serves virtually as a 5 guiding screw. For the purpose of regulating the amount of marker travel to correspond with the chart lines, a clamp and screw F^7 are provided. Connection F^8 communicates motion to the marker from the 10 Bourdon spring E by means of the pivot F^9 and the pivot block F^{10} . Adjusting screws F^{11} enable the raising or lowering of the working range of the marker F .

G designates a revolving marker release 15 adapted to hold the marker off the chart until the latter is in position or ready for the marking. The marker release G is provided with a side bar G' eccentric with G , a handle G^2 and stops G^3 adapted to hold 20 the release against or away from the marker arm F' .

A second marker, which is fixed, is designated at H which can be set at the elevation upon which it is desired to show the 25 line on the chart. The pen or indicator is shown at H' , which can be moved toward the chart by slackening the nut H^2 and sliding the marker H in the slot H^3 which lies on the radial line of the drum A . By means 30 of this fixed pen H' the accuracy of the chart can be checked, and also with it, standard lines can be drawn, in case they have not been previously provided.

The drum-supporting screw B , which is 35 preferably a double-thread of about $\frac{3}{4}$ of an inch pitch, has two nuts B' and B^2 , Fig. 1, at its upper end provided with thread engagement. By means of these nuts the drum A and screw B can be raised or lowered 40 to enable the setting of the marker pen H' so that the latter will trace over a printed line. It is necessary to slack off the tap nut and revolve the drum if the marker pen does not stand over the correct time, when 45 the chart is started.

J , Fig. 1 shows the support of the thread engaging mechanism provided with a shaft j and a conical rim roller or wheel J' with a fixed holder on the shaft of J' at the back 50 of the bearing at J^2 , so that the tension of the spring is given to the washer and support J instead of forcing the wheel J' against the screw B . The small pin J^3 prevents the shaft j and wheel J' from falling out of 55 their places when the drum A is handled off the screw B . The driver sleeve is shown at K , Figs. 1, 7 and 8, and is provided with a feather K' which engages in the feather-way B^3 on the screw B , the feather-way having a 60 depth about one-half that of the screw depth so that the wheels J' will not fall into the cut for the same. The sleeve K travels vertically only, and the clock works shown serve in the form of device illustrated merely as 65 a brake or a means for regulating the revo-

lution of cylinder A about the sleeve, since the cylinder normally tends to move helically along the screw B under the force of gravity. Obviously by using a different form of thread-engaging mechanism than 70 the wheels J' and associated parts, as for instance an ordinary nut, the combination of sleeve and clock or equivalent motor would form a positive drive instead of merely a regulating device. Such clock- 75 works connect with gear K^{11} and K^2 which are carried on the sleeve K . Gear K^{11} engages with a train of gearing to the main spring K^3 , winding key K^4 , ratchet K^5 and intermediate gears K^6 . The gear K^2 connects 80 with the timing escapement through the train of gears K^7 , escapement K^8 , balance-wheel K^9 , and hair-spring K^{10} . The clock details are of standard construction, the main spring being quite light, since the 85 weight of the drum tends to operate the clock works. When the nut B^2 is tight, the drum A can be revolved around the screw B only as the clock works permit the same. The cap A^4 over the clock works, shown in 90 Fig. 1, is dust-proof to protect the parts. Drum A is carried by the clock by means of the screws A^2 , Fig. 1, that screw into separate parts of the same.

In connection with the lower end of the 95 drum A there is provided a ring A^3 , Fig. 1, adapted to fit over and be frictionally secured to such end when the chart A' has been rolled about the drum and its edges gummed together in the manner above described. Such ring it will accordingly be seen will serve to support the chart, retaining it in whatever angular position upon the drum it may have been placed.

The chart A' , Fig. 3, is rolled around the 100 drum, as shown in Fig. 4, with the lines L and L' coinciding when laid upon the drum. To remove the chart, a knife is passed along the crease at L' leaving the narrow gummed strip remaining at the left side of the sheet 110 along the line L . The holes L^2 are provided for the purpose of filing. The lines L^3 pass along the point of the indicator H' , shown in Fig. 1, and can be either printed on the chart or plotted with the fixed pen H' . 115 These lines are standard lines and represent a known pressure or amount. If the pressure is to be changed, the screws F^7 and F^{11} can be adjusted as is necessary, using a standard test gage. The smaller subdividing lines L^4 give the amount of variation from the standard lines L^3 , it having been noted on the chart what this may be, and the amount of pressure variation from line 120 L^4 to line L^3 also noted on the regular pressure gage. The lines L^3 are noted with the hours that each line starts on the left hand side designated by number L^5 , and by the numbers L^6 on the other end of the line 125 showing the time at which the marker pen 130

F ran off the line. The lines L⁷ show the number of minutes past the hour at which the marker pen F passed along the lines L³ or L⁴. The marker pen F starts at line L on lower line L³ or L⁴ at either 12 o'clock noon or night, and place for noting this starting period is provided on the chart, as shown. When the chart is completed at the end of the twenty-four hours, the marker pen will be at the upper line L³ or close vicinity and on the line L' near the upper figure 12.

The chart, drum and clock works are removable from the case D and the screw B by giving the drum a slight turn with the hand, carrying the wheels J' over the stoppin B⁴, Fig. 6. The feather K' disengages from the screw B just previous to the time at which the wheel J' comes into contact with the pin B⁴, thereby leaving K free to revolve out of engagement with screw B, and allowing the drum to be suspended on the screw B until the attendant takes the drum out and replaces the chart with a new one. In replacing the drum ready to start the chart, it is lifted up to the end of the screw, revolved until the feather K' meets its feather-way B³ and raised up to its full height, the wheels J' recoiling back against their springs, as they are pressed back by each tooth of the screw B. The tension on these springs is quite light, as the wheels would stay to tooth without the same.

The operation of my improved recording gage is as follows: A chart is moistened at the gummed edge, placed over the drum and secured to the same. The drum is then raised up to its place; the screw B² is slackened off; and the drum, together with the screw, is revolved around to its proper time, this being the same as the regular clock would show, hour and minute. After setting the time, note is taken to ascertain if the set lines L³ correspond with the indicator H', and, if it does not, the proper adjustment is secured by means of the two nuts B' and B². The nuts B' and B² are then locked. The retractor arm G is then turned around to allow the pen F to come into contact with the chart, and the same is made to bear properly upon the chart. The marker is caused to rise above the standard set line L³ by the Bourdon spring E or to fall below said line, according as the spring is straightened out more or less by a greater or less pressure than the pressure necessary to secure a standard line L³. The amount that the marker indicates above or below the standard lines L³ is a known quantity and stated on the chart. The chart and drum are caused to rotate, and, in order to expose new portions of the chart for each time the marker travels over the chart, the drum and chart drop on the screw B an amount equal to the drop of lines L³; also equal to

the vertical distance between two adjacent lines L³. The end of one of the lines L³ is, on the drum, the beginning of the next one, thus providing one continuous thread when exposed on the drum. When the chart has run its full amount, it ceases to revolve further, and the marker F retraces its path as given by the spring tube E. Many variations of my invention may be provided without departing from the same, the spirit of which is to provide mechanism that shall pass the chart by the marker a plurality of times, and change the plane of travel each time, so as to successively expose new or untraveled portions of the chart.

Other modes of applying the principle of my invention may be employed instead of the one explained, change being made as regards the mechanism herein disclosed provided the means stated by any one of the following claims or the equivalent of such stated means be employed.

I therefore particularly point out and distinctly claim as my invention:—

1. In a recording device, the combination with a suitable marker; of a support; a chart-carrying member helically movable along the same; another member longitudinally movable along said support in unison with said chart carrying member; and braking means interposed between said two members.

2. In a recording device, the combination of a support; a chart-carrying member helically movable along the same; another member longitudinally movable along said support in unison with said chart carrying member; and means interposed between said two members and adapted to regulate the revolution of said first member about said second member.

3. In a recording device, the combination with a suitable marker; of a screw; a chart-bearing member threaded on said screw and normally tending to move along the same; a sleeve feathered on said screw; and means interposed between said member and said sleeve and adapted to regulate the movement of the former with respect to the latter.

4. In a recording device, the combination with a suitable marker; of a screw; a chart-carrying member threaded on said screw and normally tending to move along the same; a sleeve feathered on said screw; and braking means interposed between said cylinder and said sleeve.

5. In a recording device, the combination with a suitable marker; of a screw; a chart-carrying cylinder threaded on said screw and normally tending to move along the same; a sleeve feathered on said screw; and braking means interposed between said cylinder and said sleeve.

6. In a recording device, the combination with a suitable marker; of a screw; a chart-

carrying cylinder threaded on said screw and normally tending to move along the same; a sleeve feathered on said screw; and clock-works interposed between said cylinder and said sleeve.

5. In a recording device, the combination with a suitable marker; of a screw; a chart-carrying cylinder threaded on said screw and normally tending to move along the same; a sleeve feathered on said screw; and clock works attached to said cylinder and connected with said sleeve.

8. In a recording device, the combination with a suitable marker; of a screw; a chart-carrying cylinder threaded on said screw and normally tending to move along the same; a sleeve feathered on said screw; and clock-works interposed between said cylinder and said sleeve whereby the revolution 10 of the former about the latter is regulated.

9. In a recording device, the combination with a suitable marker; of a vertical screw; a chart-carrying member threaded on said screw and tending to move along the same 15 under the force of gravity; a sleeve feathered on said screw; and regulating means interposed between said member and said sleeve.

10. In a recording device, the combination with a suitable marker; of a vertical screw; a chart-carrying cylinder threaded on said screw and tending to move helically along the same under the force of gravity; a sleeve feathered on said screw; and clock-works interposed between said cylinder and 20 said sleeve and regulating the revolution of the former about the latter.

11. In a recording device, the combination of a screw-threaded support; a chart-carrying cylinder; and thread-engaging 25 mechanism on said cylinder adapted to secure the same to said support, and comprising a plurality of substantially radially disposed shafts, rollers mounted on the inner ends of said shafts, and springs pressing said shafts inwardly, so as to hold said rollers into engagement with the threads of said support.

12. In a recording device, the combination of a screw-threaded support; a chart-carrying cylinder; thread-engaging mechanism on the latter comprising a plurality of substantially radially disposed shafts and rollers mounted on their inner ends and adapted to engage the threads of said support; a sleeve 30 longitudinally movable along said support; and braking means interposed between said cylinder and said sleeve.

13. In a recording device, the combination of a screw-threaded support; a chart-carrying cylinder; thread-engaging mechanism on the latter comprising a plurality of substantially radially disposed shafts and rollers mounted on their inner ends and adapted to engage the threads of said support; a sleeve longitudinally movable along 35

said support; and clock-works interposed between said cylinder and said sleeve whereby the revolution of the former about the latter is regulated.

14. In a recording device, the combination with a suitable marker; of a support; a chart-carrying member helically movable along the same; another member longitudinally movable along said support; and clock mechanism connecting said first member to 70 said second.

15. In a recording device, the combination with a suitable marker; of a screw; a chart-carrying member threaded on the same; a sleeve feathered on said screw; and 80 clock mechanism connecting said chart-carrying member to said sleeve.

16. In a recording device, the combination with a suitable marker; of a screw; a chart-carrying cylinder threaded on the same; a 85 sleeve feathered on said screw; and clock-works interposed between said cylinder and said sleeve and adapted to revolve the former about the latter.

17. In a recording device, the combination of a supporting case; a revolvable cylinder movable axially through such case and adapted to carry a chart; a screw carrying said cylinder and fastened at one end of said case; clock-works connected to said cylinder and to a sleeve provided with a feather, 90 engaging feather-ways in said screw, and adapted to effect a revolution of the cylinder around the screw at a predetermined speed, the construction being such that said revolution is effected a plurality of times, and said cylinder is moved axially through said case a predetermined distance each revolution; a marker bearing upon the chart; means connecting said marker with the pressure to be recorded; means for regulating the force with which said marker contacts the chart; and means for throwing said marker out of engagement with the chart. 100

18. In a recording device, the combination of a screw-threaded support; a chart-carrying member; and means resiliently mounted on said member and adapted to engage said threaded support when moving in one direction longitudinally therealong, 110 and to slide over the same when moved in the opposite direction.

19. In a recording device, the combination of a screw-threaded support; a chart-carrying member; and thread-engaging mechanism on the latter comprising a plurality of substantially radially disposed shafts, rollers mounted on the inner ends of said shafts, and springs pressing said shafts inwardly, 115 the form of said screw-thread and the arrangement of said shafts being such as to permit a sliding longitudinal movement of said mechanism in one direction along said thread.

20. In a recording device, the combination 120

with a support, of a screw mounted in said support so as to be independently longitudinally and rotatably adjustable therein, a chart-carrying member threaded on said screw, and a marker adapted to mark on said member.

21. In a recording device, the combination of a screw; a chart-carrying member threaded, and a sleeve feathered on said screw, the disposition of said member and sleeve being such as to permit the latter to become disengaged from said screw prior to the former; and means for arresting the movement of the former upon the disengagement of the latter.

22. In a recording device, the combination of a screw; a chart-carrying member threaded, and a sleeve feathered on said screw, the disposition of said member and sleeve being such as to permit the latter to become disengaged from said screw prior to the former; and a pin at the end of said screw adapted to arrest the movement of the former upon the disengagement of the latter. 20

Signed by me, this 15th day of January, 25
1904.

WILLIAM L. MORRIS.
